(57) **CLAIM**

The ornamental design for an exercise garment, as shown and described.

DESCRIPTION

FIG. 1 is a front view of an exercise garment showing my new design with the zippers thereof in a closed position;

FIG. 2 is a rear view thereof;

FIG. 3 is a side view thereof;

FIG. 4 is an opposite side view thereof;

FIG. 5 is a perspective view thereof;

FIG. 6 is a top view thereof; and

FIG. 7 is a bottom view thereof;

FIG. 8 is a front view of the exercise garment showing my new design with the zippers in a partially open position;

FIG. 9 is a rear view thereof;

FIG. 10 is a side view thereof;

FIG. 11 is an opposite side view thereof;

FIG. 12 is a perspective view thereof;

FIG. 13 is a top view thereof; and,

FIG. 14 is a bottom view thereof.

The broken lines along the surfaces of the exercise garment depict features that form no part of the claimed design. The zipper elements outlined by broken lines depict portions of the exercise garment that form no part of the claimed design.

1 Claim, 14 Drawing Sheets
